United States Patent Office

Des. 204,166
Patented Mar. 22, 1966

204,166

BOTTLE

Willard F. Meyers, Toledo, Ohio, assignor to Owens-Illinois Glass Company, Toledo, Ohio, a corporation of Ohio

Filed Apr. 1, 1965, Ser. No. 84,549

Term of patent 14 years

(Cl. D58—8)

FIG. 1

The dominant feature of my design resides in portions shown in full lines.

I claim:

The ornamental design for a bottle, substantially as shown and described.
